TRANSMITTER TUBE FOR ULTRA-SHORT WAVES

Fritz Schröter, Berlin, Germany, assignor to Telefunken Gesellschaft für Drahtlose Telegraphie m. b. H., Berlin, Germany, a Corporation of Germany

Application March 9, 1933, Serial No. 660,144, and in Germany December 29, 1931

4 Claims. (Cl. 179—171)

In the generation of extremely short waves, especially those of an order of one decimeter by the use of the Barkhausen-Kurz circuit scheme wherein there is impressed on the grid of a tube a high positive potential and to the anode a low negative or low positive potential in reference to the filament, it is necessary to choose the loss energy which a tube may be expected to sustain, as high as possible. In the case of a Barkhausen-Kurz tube certain problems, especially of a thermal nature, different from those in standard or conventional tubes are found to arise. In the latter types it is only the anode or plate that carries a thermic load inasmuch as it carries almost exclusively the entire emission current, and since it operates at high potentials in reference to the cathode or filament. In the Barkhausen-Kurz circuit arrangement, however, only the grid carries a thermal load, whereas the plate is free from any appreciable electric energy. Indeed, the plate becomes heated merely by virtue of radiations impinged thereon from the grid and the filament.

Now, for reasons of absolutely imperative capacity reduction in the Barkhausen-Kurz tube it is necessary to make the grid of especially limited area, and this very fact tends to aggravate and accentuate the thermal problem before referred to.

Now, by the ways and means hereinafter disclosed the solution of the above-mentioned problem in transmitter valves for ultra short waves, especially in the Barkhausen-Kurz circuit scheme, is facilitated and a substantial progress in the design and construction of such tubes is obtained. The invention more particularly consists in that the grid, by ways and means known in the earlier art of tubes, is rendered black or rough superficially by suitable treatment, with a view to make the same especially efficient for thermal radiation, while at the same time the plate surrounding the grid has the form of an apertured hollow body, preferably of the shape of a wire network or gauze. In this way, conditions are made so that higher current load of the grid can be combined with limited electrode area or surface without incidentally endangering the plate by marked heat radiation. In addition to the fact that the yielded power can be increased, the said scheme offers this further merit that the length of the

resultant or generated waves or oscillations is reduced owing to the reduction in the capacity. The substance employed for blackening the grid could be used at the same time as a getter. For this purpose zirconium has been found to be eminently suited. 55

A transmitting circuit which may be used with the present invention is shown in the single accompanying drawing wherein there is shown means for transmitting modulated telegraph signals over a Barkhausen-Kurz circuit by means of a key. In the drawing is shown a Barkhausen-Kurz tube 1 whose grid is blackened and/or roughened for thermal radiation purposes, and whose plate comprises a perforated gauze-like material. Suitable sources of potential 2 and 3 supply the grid and anode with high positive and low negative potentials, respectively, as shown. The modulated oscillations produced by the operation of telegraph key 4 are transmitted over a bi-polar antenna 5, the positive grid potential being prevented from entering the antenna and parallel leads extending from the tube thereto by blocking condenser 6. It will be understood, of course, that telephonic modulating means may be substituted for telegraph key 4, if desired. 75

I claim:

1. An ultra short wave oscillation generator comprising an electron discharge device having a cathode, anode and control electrode, means for applying a high positive potential to said control electrode, and a much lower potential to said anode relative to said cathode, the surface of said control electrode being blackened for aiding thermal radiation and said anode being perforated 80 whereby there is obtained a reduction in capacity between said anode and control electrode. 85

2. An ultra short wave oscillation generator comprising an electron discharge device having a cathode, anode and control electrode, means for applying a high positive potential to said control electrode, and a much lower potential to said anode relative to said cathode, the surface of said control electrode being blackened and roughened for aiding thermal radiation and said anode being 90 perforated whereby there is obtained a reduction in capacity between said anode and control electrode. 95

3. An ultra short wave oscillation generator comprising an electron discharge device having a 100

cathode, anode and control electrode, means for applying a high positive potential to said control electrode and a much lower potential to said anode relative to said cathode, the surface of said control electrode being treated for aiding thermal radiation and said anode being perforated whereby there is obtained a reduction in capacity between said anode and control electrode.

4. An ultra short wave communication circuit 10 for transmitting modulated oscillations of the order of a meter and less, comprising an electron discharge device having a cathode, anode and control electrode, means for applying a high posi-

tive potential to said control electrode and a much lower potential to said anode relative to said cathode, the surface of said control electrode being treated for aiding thermal radiation and said anode being perforated whereby there is obtained a reduction in capacity between said anode and control electrode, and suitable modulating apparatus intermediate said control electrode and said means for affecting the oscillations to be transmitted in accordance with the desired message to be transmitted.

FRITZ SCHRÖTER.
